UNITED STATES PATENT OFFICE

LUCIEN G. PONCE, OF PARNASSUS, PENNSYLVANIA, ASSIGNOR TO ALLEGHENY STEEL COMPANY, OF BRACKENRIDGE, PENNSYLVANIA, A CORPORATION OF PENNSYLVANIA

PIPE THREAD PROTECTOR

Application filed January 15, 1931, Serial No. 508,849.

This invention relates to pipe thread protectors of the type employed to envelop the threaded ends of pipe to protect the threads from injury in shipping or handling, and the present invention is a modification of the thread protector disclosed in my co-pending application, serially numbered 481,900, filed September 15, 1930, and since issued as Patent No. 1,885,375, of November 1, 1932.

10 In the aforementioned application is described a pipe thread protector made of relatively thin gauge metal which is formed to produce a structural section of great strength and which is secured to the pipe by means of 15 a metal clip which interacts with the protector and the thread of the pipe to form an interlock.

The general structural features of the protector are retained in the present invention but the disposition and function of the interlocking element is greatly modified, as will become apparent from the several views of the accompanying drawing in which like reference characters designate like parts and in 25 which Figure 1 and Figure 2 are side and end elevational views, respectively, of a pipe thread protector embodying the principles of this invention; Figures 3 and 4 cross sectional views corresponding to the views of 30 Figures 1 and 2 taken along the lines III—III of Figure 2 and IV—IV of Figure 1, respectively; Figure 5 a cross sectional view illustrating the application of the invention to an internally threaded pipe; and Figure 6 35 a view in perspective of an interlocking clip employed in the manner hereinafter described.

With reference to Figures 1 to 4 inclusive of the drawing, 1 designates a pipe, 2 a metal sleeve, the inner dimensions of which are such as to permit the sleeve to freely slide over the end of the pipe 1. The ends of the sleeve 2 are crimped as at 3 and 4 to form beads 5 and 6 which are of greater diameter 45 than the outer dimensions of the sleeve 2, and which constitute the sleeve a structural section of great strength.

The turned over end 7 of the sleeve constitutes an abutment for the end of pipe 1 and 50 the protector sleeve is secured to the pipe by

an interlocking clip member 8. The side of the sleeve is slotted at 9 and 10, the slot being of sufficient width to receive the clip 8 which is of V shape shown in Figure 6 of the drawing.

55 The sides of the V are inserted in the slots 9 and 10 and by striking a blow at the top of the V, the sides and legs are diverted in the manner shown in Figures 2 and 4 of the drawing, so that the ends 11 intimately engage the thread of pipe 1, thus interlocking the sleeve with the pipe. To remove the thread protector, a wedge shaped tool or hook is inserted beneath the clip to pull it out of 60 the thread, or the sleeve may be unscrewed 65 from the thread of the pipe. The clip 8 is preferably of a metal softer than the pipe thread to prevent damage to the latter when the clip is driven home to effect the interlocking engagement therewith, and a suitable 70 metal for this purpose is aluminum, although copper and mild steel may also be employed.

In Figure 5 of the drawing is illustrated a pipe 1 in which the thread is applied internally instead of externally as in Figure 3 for example. The pipe protector sleeve 12 is modified to adapt it to fit within the pipe and the ends of the sleeve 12 are crimped as at 15 and 14 in the reverse manner of the crimping and the external form of the protector to also form 80 an abutment at 15 and a strengthening bead at the inner end of the sleeve. The internal protector is slotted in the same manner as the external protector and a clip 8 is applied to 85 interlock with the thread to secure the protector in place in the manner described in connection with Figure 4 of the drawing.

It will be evident from the foregoing description of the invention that pipe thread protectors made in accordance therewith are 90 of relatively inexpensive construction, employing a minimum amount of metal due to the relatively thin section of gauge of the metal as it is unnecessary to cut a thread in the protector sleeve, as in the prior art devices, and by means of the interlocking clip the protector is intimately engaged with the thread of the pipe without causing any damage, and without requiring that the protecting sleeve be screwed on or off the end of the 95 pipe.

5 pipe. By employing a clip of the nature described herein, the protector is interlocked with a greater number of threads than in the form of my aforesaid application, thereby assuring a more positive engagement of the protector with the pipe. Although one embodiment of the invention has been herein illustrated and described, it will be obvious to those skilled in the art that various modifications may be made in the details of construction without departing from the principles herein set forth.

10

I claim:

15 1. A pipe thread protector comprising a metal sleeve having its ends crimped to form beads of greater diameter than the outer diameter of said sleeve to constitute the sleeve a structural section, said sleeve having an inner diameter sufficiently greater than the outer diameter of the pipe thread to permit the sleeve to freely slide on said thread, said sleeve being further provided with a pair of parallel slots axially disposed between the beaded ends of said sleeve, and a clip extending between said slots on the outside of the sleeve and having its ends extending in said slots for intimate engagement with the threads of the pipe.

20

25

30 2. A pipe thread protector comprising a metal sleeve having its ends crimped to form beads of greater diameter than the outer diameter of said sleeve to constitute the sleeve a structural section, said sleeve having an inner diameter sufficiently greater than the outer diameter of the pipe thread to permit the sleeve to freely slide on said thread, said sleeve being further provided with a pair of parallel slots axially disposed between the beads of said sleeve and a relatively wide
35 40 clip of soft metal extending between said slots on the outside of the sleeve and having its ends extending in said slots for intimate engagement with a plurality of the threads of the pipe.

45 In testimony whereof I have hereunto set
my hand.

LUCIEN G. PONCE.
